UMBRELLA DOLL

Mary C. Hawkey, Philadelphia, Pa.

Application October 30, 1943, Serial No. 508,306

3 Claims. (Cl. 46—151)

This invention relates to umbrellas and is concerned primarily with an umbrella which is made in simulation of a doll.

The invention has in view, as its foremost objective, the provision of an umbrella which when in closed position gives the appearance of a doll. In carrying out this idea, the lower portion of the umbrella stem takes the form of the legs and lower portion of the doll.

A particularly important object lies in the provision of an umbrella doll, of the character aforesaid, in which the lower portion of the doll's body is made as a tubular member surrounding the umbrella stem, thereby providing a recess into which is fitted the movable arms of the umbrella when the latter is in closed position.

In providing an umbrella doll in accordance with the above noted ideas, the umbrella canopy represents the skirt of a doll's dress when in closed position. A further object is the provision of a doll's head and arms, together with clothing for the upper portion of the doll on the exterior of the canopy. When these objectives are achieved, there is provided a novelty in the form of an umbrella which, when closed, constitutes, in all respects, a child's doll, but which may be opened to serve as an umbrella when such use is required.

Various other more detailed objects and advantages of the invention, such as arise in connection with carrying out the above noted ideas in a practical embodiment, will in part become apparent and in part be hereinafter stated as a description of the invention proceeds.

The invention, therefore, comprises an umbrella doll consisting of the usual umbrella canopy, together with its supporting ribs, movable arms and stem. The canopy itself constitutes the skirt of a doll's dress, while the lower portion of the stem carries a tubular part providing a recess about the stem for receiving the arms, and which tubular part represents the lower portion of a doll's body. This tubular part is continued down into a structure simulating the legs of the doll. On the exterior of the canopy is carried a doll's head, together with a doll's arms and suitable clothing for the upper portion of the doll.

For a full and more complete understanding of the invention, reference may be had to the following description and accompanying drawing, wherein:

Figure 1 is a view showing the umbrella doll in closed position;

Figure 2 shows the umbrella opened; and

Figure 3 is an enlarged detailed showing of the structure carried by the lower portion of the umbrella stem.

Referring now to the drawing, wherein like reference characters denote corresponding parts, and first more particularly to Figure 2, the canopy of the umbrella is referred to in its entirety by the reference character C and is shown as comprising a plurality of the usual ribs 10 over which is fitted the usual water proof fabric 11.

Referring now more particularly to Figure 3, it will be noted that the umbrella also includes a stem 12 over which is fitted the usual operating slide 13. Gathered at and secured to the slide 13 are the usual movable arms 14, which, at their upper ends, are pivotally secured to the ribs 10. The stem 12 is continued down an appreciable distance below the slide 13, where it is anchored to a body structure 15 which is made in simulation of the lower portion of a doll's body. It will be noted that the upper portion of the structure 15 is tubular in form providing a recess 16, which receives the arms 14 when the umbrella is in closed position. The lower portion of the structure 15 takes the form of the doll's legs shown at 17.

Carried by the stem 12 outside and above the canopy C is the doll's head 18. Immediately below the head 18 are a pair of doll arms 19 which 30 may carry the doll clothes, such as a small coat or jacket shown at 20.

It is evident that when the canopy C is opened, in the position shown at Figure 2, all of the utilitarian functions of an umbrella are provided, and a child will be properly shielded from the rain or sun's rays, as occasion demands. But, with the umbrella closed, in the position shown in Figure 1, there is provided for all essential purposes a doll. In this position, the canopy C acts as the doll's skirt. The arms 19 assume the normal position illustrated, and the jacket 20 completes the doll's apparel. The feet 17 project beneath the skirt, and the head 18, being carried at the upper end of the stem 12, assumes its proper position.

While a preferred specific embodiment of the invention is hereinbefore set forth, it is to be clearly understood that the invention is not to be limited to the exact constructions illustrated and described, because various modifications of these details may be provided in putting the invention into practice, within the purview of the appended claims.

What is claimed is:

55 1. In a doll of the character described, a stem,

a canopy carried by said stem including supporting ribs and a fabric, a slide on said stem, supporting arms attached to said ribs and gathered at and secured to said slide, a doll body structure carried by the lower end of said stem and providing a recess about said stem adapted to receive said slide, and arms and doll body structure carried by upper end of said stem exteriorly of said canopy.

2. In a doll of the character described, a stem, a canopy carried by said stem including supporting ribs and a fabric, a slide on said stem, supporting arms attached to said ribs and gathered at and secured to said slide, a doll body structure carried by the lower end of said stem and providing a recess about said stem adapted to receive said slide, and arms and doll body structure carried by upper end of said stem exteriorly of said canopy, said doll body structure comprising a head, doll arms and clothing for the upper 20 portion of a doll.

3. In a doll of the character described, a main supporting stem, a doll body structure carried by the lower end of said stem and providing a recess about said stem, doll body structure carried by the upper end of said stem comprising a head, doll arms, and clothing for the upper portion of a doll, and a skirt interposed between said lower and upper doll body structures, said skirt taking the form of a canopy that is adapted to assume either a closed position enveloping the lower doll body structure or an open position supporting said doll arms, ribs pivotally mounted on said stem and supporting said skirt, a slide on said stem, and supporting arms connected to said ribs and said slide, said slide being adapted to being received in said recess when said skirt is in closed position.

MARY C. HAWKEY.
